UNITED STATES PATENT OFFICE

EDWARD P. HOLMBERG, OF OKLAHOMA CITY, OKLAHOMA

GAME APPARATUS

Application filed October 20, 1928. Serial No. 313,830.

This invention relates to games of that character wherein tiles are used for playing pieces, and the object of the invention is to provide a game which requires good judgment, quick thought, which is capable of being played by five, four, three or two persons, and which is capable of many variations.

A further object is to provide a set of tiles for this purpose which are capable of use for playing a large number of variations of the same game.

Other objects will appear more particularly in the course of the following description.

My invention is illustrated in the accompanying drawings wherein—

Figure 1 is a plan view of the tray employed in the game apparatus constructed in accordance with my invention;

Fig. 2 is a side elevation thereof;

Fig. 3 is a combined plan of the tiles employed;

Fig. 4 is a sectional view of a tile compartment;

Fig. 5 is a side elevation of the rack showing the tile in position therein;

Fig. 6 is a plan view of the rack;

Fig. 7 is an end elevation of the rack;

Fig. 8 is a side elevation of one of the pegs; and

Fig. 9 is a side elevation of the marbles.

Before describing the method of playing the game I will describe the apparatus which is to be used therefor. As illustrated in Fig. 1, the revolving rack and discard tray is mounted upon a base 10.

The tray or rack 12 is disposed upon a table and rotated. The tray or rack is divided adjacent its periphery into thirty separate compartments 14 by the radially disposed partitions 15 which are preferably made of felt or like material. The back of each compartment 14 is formed by a felt wall 16. The partitions 15 preferably extend inward beyond the back so as to form buffers 17. The central discard tray 18 is provided adjacent the wall 16 with a plurality of shallow sockets 19 in which marbles may come to rest. The margin of the base 10 which extends beyond the rotatable rack

is formed at a plurality of points with openings 20 for the reception of pegs or pointers 21. These openings 20 are so arranged that five pegs or pointers may be used if five persons are playing and the pointers will be equidistant from each other or four pegs may be used, or three, or two, and these pegs or pointers will always be equidistant. The perforations 20 to be used under these circumstances are preferably indicated by numerals 2, 3, 4 or 5. The pointers are preferably split at their upper ends and a flexible pointer or indicator 22 is disposed within these split upper ends.

The playing pieces or tiles 23 are ninety in number and are divided into five suits or colors as shown in Fig. 3, of eighteen tiles each. These different suits are differentiated by designs representing certain flowers and are called respectively—Pansy, Daisy, Violet, Rose or Clover, or they may be referred to by colors as—Pansy as purple, Daisy as yellow, Violet as blue, Rose as red, Clover as green, but preferably the flower names will be used. Each of the five suits is divided into four sections. One of these sections contains three tiles and this section is called "Games". The other three sections have five tiles each and are called respectively: Doubles, Singles, and Blanks.

The five tiles of each section of any suit have spots or flowers arranged thereon from one to five, inclusive, and carry numerals at the left hand corner of each tile corresponding to these spots, as for instance, 1, 2, 3, 4, and 5, so that a tile may be designated—1 Blank Pansy, or 3 Single Rose, or 2 Double Clover, etc.

The three tiles of each suit in the Games section have only one design or flower on each tile, but the several tiles are designated by the Roman numerals I, II and III and may be designated or referred to, for instance, as "Single Violet Game", "Double Daisy Game", or "Triple Rose (or Daisy or Violet) Game".

In order to differentiate between the several sections, the flowers on the Blanks section may have a short stem, the flowers on the Singles section may have a longer stem

with leaves, and the flowers on the Doubles section have a vine with leaves connecting all the flowers on the tile.

The tiles of the Games section have a different design of flower for instance than that used for the Singles, Doubles and Triples. The numerals at the upper righthand corner of each tile designates the scoring value of the tiles. The tiles of the Blanks section have no scoring value, but under certain circumstances they will increase the score and under certain circumstances will make a scoring hand out of an otherwise non-scoring hand. The designs and numerals on the tiles are such that the tiles may be read from opposite directions.

Five marbles (see Figure 6) are used for the purpose of indicating the suits for the several players and these will correspond in color to the colors of the several suits, thus, for instance, there will be five marbles colored respectively purple, yellow, blue, red and green.

Each player has before him a tile rack comprising a base 24 and a back rest 25 which is operatively hinged to the base so that it may be turned in an approximately vertical position or turned into a horizontal position, any suitable means being provided for holding the rest 25 in an approximately vertical position so that a tile may rest thereagainst. This back or rest 25 both for the convenience of the player in arranging his tiles and for the purpose of playing certain games or variations of games must be divided into sections, colored red, blue, yellow, purple, etc., or ornamented in correspondence with the indications on the tiles of the various suits.

The base 24 of the tile rack is provided with upwardly projecting pins 26. There will be ten of these pins and 275 counters 27 which are in the form of flat disks which will

Pansy
Daisy
Violet
45 Rose
Clover

be used in connection with these pins.

At the beginning of the game all of the counters 27, which counters are colored red, 50 blue, green, yellow and purple, will be disposed on the five pins on the left hand side of the rack, and as the player scores the appropriate counters will be moved over to the pins on the right hand side of the rack.

55 The tiles will be contained in trays 37 by which the tiles will be kept in proper order under normal circumstances, these trays being capable of being used also for a form of solitaire.

60 By using not over five designs or spots on any one of the playing pieces or tiles and combining these with the numerals placed at the upper left hand corner of each tile, the players are enabled to accurately determine 65 the number of spots on the tile at a glance.

The numerals on the upper right hand corner of the tiles show the scoring value thereof and this enables the players, during play, to readily determine the value of their hands and at the close of the game to quickly compute their scores without having to refer to any schedule.

The revolving tile rack and discard tray enables each of the players to draw and discard without being compelled to reach across the discard tray and obstruct the view of other players, as the rack may be turned so that any player may secure the tile which he desires. It further eliminates the disagreeable feature of the tiles being accidentally disarranged by some player in drawing or discarding in playing, as sometimes occurs if tiles are racked and discarded on the table. The partitions 15 being of felt and the bottoms of the compartments 14 being felt lined, 85 permits the rack to be revolved at considerable speed without the tiles slipping out of the compartments. The use of the hinged or pivoted tile rest permits the players to expose their hands by tilting the rests with 90 the tiles thereon backward to the table without changing the upright or vertical position of the counter rack or disturbing the counters.

The use of pins for retaining the counters prevents the counters from being accidentally 95 pushed or knocked from the table and enables the players to move their racks from table to table without disarranging the counters.

The use of the apparatus will be understood by reference to the following general rules. These rules are given for one game, as it is not believed necessary to indicate all the games which might be played with this apparatus. The scoring value of each tile in the different suits and sections are in points as follows:

Singles 30, Doubles 60, I Game 30, II Game 60, III Game 90
Singles 25, Doubles 50, I Game 25, II Game 50, III Game 75
Singles 20, Doubles 40, I Game 20, II Game 40, III Game 60
Singles 15, Doubles 30, I Game 15, II Game 30, III Game 45
Singles 10, Doubles 20, I Game 10, II Game 20, III Game 30

If there are five players, the following procedure is used:

The pointers for the several players are placed in the holes 20. This will dispose the five players equidistantly around the rotatable rack. The tile racks are disposed one for each player and all of the playing tiles are placed on the table face down and shuffled. Then the tiles are taken at random and placed three tiles face down in each compartment on the tile rack. The 11 counters of each color are placed on the counter racks starting at the extreme left pin and placing the green counters on this pin, then the red, blue, yellow and purple, leaving the five pins at the right end of rack vacant for reception of counters won during play.

After all tiles are placed in the rack and each of the players have their counter racks,

one of the players will then place the five suit marbles in the discard tray 18, then start rack revolving at a moderate speed and when rack stops and the marbles have seated in 5 some of the depressions in the bottom of the tray, each player will remove the marble nearest his pointer, placing the marble on his tile rack, the small depression in the lower member of rack will keep the marble in place, 10 the colors of the marbles designates each players own suit, the purple marble designates Pansy, yellow is Daisy, blue is Violet, red is Rose and green is Clover.

Initial draw.—The player having the purple marble will now give rack a slight spin 15 and when rack stops each player draws six tiles from the top tier in the compartments starting at his pointer for the first tile and drawing five more to the right and placing 20 the tile as drawn on his tile rack with face of tile toward him. The same player again spins the rack and when rack stops each 25 of the players draws five tiles from the second tier in the compartments and starting at his pointer for the tile and drawing 4 more to the right again placing these tile on the tile rack as in the first draw.

Each player should now have 11 tiles on his tile rack and should arrange the tiles so 30 that the Blanks, the Singles and the Doubles and the Games will be separated and each section then arranged according to the number of spots on the tile.

After each player has made an initial 35 draw of tile there should be 5 tiles in the second tier and 30 tiles in bottom tier, then remaining in the compartments of the tile rack, these are the "closed tile" in the draw and discard and the discarded tile are "open tile".

Draw and discard.—It is now the purpose 40 of each player, by drawing and discarding that he may obtain a section of Singles containing the 1, 2, 3, 4 and 5 spots, a section of 45 Doubles, containing the 1, 2, 3, 4 and 5 spots, and a Game tile, all preferably of the highest scoring values or in the player's own suit.

The sections may be made up of mixed 50 suits but have to contain the 1, 2, 3, 4 and 5 spots to become a scoring section. Each of the sections may contain either 1 or 2 Blanks having the same spots as the lacking Singles or Doubles, the use of the Blanks thus making a scoring section whereas a section not containing the 1, 2, 3, 4, 5 in rotation would not score. The Game tile may be of any suit.

The player having the purple suit marble 55 will commence the draw by taking 1 of the 60 5 tiles from the second tier in the tile compartments of the tile rack and placing same on his tile rest and should the tile drawn help his hand he will then discard some other tile from his tile rest by placing this tile face 65 up in the discard tray, should the drawn tile

not help his hand he may discard this by placing same face up in the discard tray.

The next player to the left will now draw 70 1 tile from the second tier in the compartments or he may draw the tile that is in the discard tray should he so desire and discarding in the manner of the first player, the draw and discard again passing on to the left and so on around the table, each of the players drawing and discarding in their turn. 75

The tiles in the upper tier in the compartments should all be drawn before drawing any tile from the lower tier, the player in 80 his turn may draw any one of the tiles from a tier in the tile compartments or from the discard tray, but should the tile wanted be on the opposite side of the rack or tray from the player, he should not reach across the discard tray to draw, but must turn the rack 85 bringing the tile wanted in front of him so as not to obstruct the full view of the discard tray from the other players.

When a player has acquired a complete hand 90 containing a Single and a Double section and a Game tile, the tile in one section being all of the same suit, he may declare Unique, this terminating any further drawing or discarding by the other players.

All players will now expose their hands 95 on their rest by tilting the rest 25 backwards onto the table bringing the tiles to the full view of all players and leaving the rest 25 and tiles in this position until all scores have been counted and settled. 100

The score.—Total the score of each section separately by adding together the numerals at the upper right corner of each tile in the section, combine these two totals and should the hand also contain a Game tile 105 add its scoring value to the section totals making the straight score of a hand.

If a hand contains a section with all tile 110 of the same suit and a Double Game tile in the corresponding suit it will double the combined scores of the section and the Game tile. Should both of the sections and the Double Game tile be in the same suit, it will double the combined scores of both sections and the game tile. 115

Should the Game tile be a Triple Game and the same suit as either or both sections, it triples the combined scores of the respective sections and the Game tile. 120

The straight score plus any doubles or triples is termed the original score.

The players should always bear in mind 125 that any section to score must contain the 1, 2, 3, 4 and 5 spots and that a section can not contain more than two Blanks, that the sections of Singles cannot contain any Doubles or Games, that the section of Doubles shall contain no Singles or Games, that a Game tile cannot score without one of the sections being a scoring section, and that Unique should 130

never be declared without the player so declaring having a Game tile and a full suit section included in his hand.

Forfeits.—A player drawing out of his turn 5 and the draw is called to his attention by another player must place the drawn tile face up in the discard tray and will forfeit one green counter by placing same in the discard tray.

10 A player having less than the 11 tiles on his rest after he has discarded and is so advised by another player must immediately draw the lacking tile from the open tile in the discard tray then forfeit one red counter.

15 A player having more than the 11 tile on his rest after he has discarded and is so advised by another player must then allow the player to his left to draw the surplus tile from his rest and to place same face up in the 20 discard tray and will forfeit one blue counter for each surplus tile drawn from his rest.

A player declaring Unique without having the one complete full suit section, but having both sections in mixed suits, and a Game tile 25 will forfeit one yellow counter by placing it in the discard tray, and is also disqualified from acting as Cashier, the first player to his right having a Unique hand must then act as Cashier.

30 A player declaring Unique and having one section complete in a suit and the other section complete in a mixed suit but no Game tile, will forfeit one purple counter by placing it in the discard tray, and is also disqualified 35 from acting as Cashier, the first player to his right having a Unique hand must then act as Cashier.

A Unique hand may have both sections in 40 one suit, or one section may be of one suit and the other section in another suit and the Game tile may be in any suit, but the tiles in one of the sections must all be in the same suit to declare Unique.

45 A player declaring Unique and having a non-scoring hand must pay to each of the other players the amount of their respective total scores and is also deprived of the benefits of the counters in the discard tray, these being left in the tray for the next Cashier.

50 A total score is the original score plus the benefits a player is entitled to.

A player, after declaring Unique becomes the Cashier and is so termed because he both pays and collects when scores are paid, and is 55 also entitled to certain special benefits as compensation for acting as Cashier.

A player declaring Unique on an incomplete hand cannot act as Cashier.

Benefits—For Cashier only.—The player 60 declaring Unique and becoming Cashier will first total his original score represented by his hand and add 100 points for acting as Cashier.

Should there be any forfeited counters in 65 the discard tray he will total the amount in 15 points represented by such counters and add

that number of points to his score and will remove the counters from the discard tray and place them on his own counter rack as a further benefit.

Should he declare Unique on the last closed tile that was in the compartments when his turn came to draw, he will add 200 points to his score, in this case he must expose the tile so drawn to the other players before placing it on his tile rest.

Should he declare Unique on the lowest possible score in a full suit hand (both sections and single game in Clover suit) he will add 300 points to his score.

Should he declare Unique on the lowest possible score in a mixed hand (single section in Clover suit containing 3 Single and 2 Blank tiles, double section containing 3 Doubles in Clover suit and 2 Blank tiles in any other suit and Single game in Rose suit) he will add 400 points to his score.

Benefits—For all players.—A player having one section complete in own suit will add 100 points to his score.

A player having one section complete and a Game tile or both sections complete in his own suit will add 200 points to his score.

A player having both sections complete and also holding a Game tile, all being in his own suit, adds 300 points to his score.

A Game tile in the players own suit will not entitle the player to benefits unless one of the sections is also in his own suit.

All benefits are added after the original scores have been determined as no benefits are doubled or tripled.

The scoring values of all benefits given in the foregoing schedules may, at the option of the players be lowered to use tens instead of hundreds as scheduled.

Paying the scores.—When all players have each determined their own total scores, that is their original score plus any benefits, they may be entitled to, the Cashier first collects from each player who has a lower score than himself the difference in points between his total score and player's total score, the Cashier placing the counters so collected on his own counter rack, then the Cashier pays to the players having a higher score than himself the difference in points between such player's total score and his total score, these players then placing the counters so collected on their counter racks.

When all the scores are settled a new hand is started, the tiles all being placed face down on the table and shuffled and then placed in the compartments on the tile rack as in the original set up and the game then continues as in the previous hand until some player again declares Unique.

Each player retains his own counter rack for the full duration of the game and at the termination of play the player who has the

highest number of points represented by the total counters on his rack is the winner.

The termination of a play is usually when five hands are played to completion or a certain time may be set for the game.

Forced Unique.—Should none of the players have declared Unique before the last tile in the compartments is being drawn, the drawing of it prohibits the declaration of Unique by any other player except this player drawing this last tile, and should this player then be unable to declare Unique, all further drawing from the discard tray terminates and Forced Unique is declared by the player holding the purple suit marble as own suit.

This player now becomes Cashier regardless of whatsoever hand he may possess and he will receive the benefits, collects and pays in the same manner as Cashier in Unique, all players totaling their scores being and all scores paid as in Unique.

Should this Cashier have a non-score hand he will have a total score of 100 points plus the points represented by any forfeited counters that may be in the discard tray.

After all scores are settled a new hand is now started in the same manner as in Unique.

A few sample hands and scores.—The different suits are indicated by the first letters in the suit names as P—Pansy, D—Daisy, V—Violet, R—Rose, and C—Clover.

The highest possible original score requires the single section, the double section and the triple game tile all to be in the Pansy suit, and no blanks in either section. This hand scores as follows—single section each tile 30 points is 150,—double section each tile 60 points is 300, game tile 90 points equals 540 points as straight score and multiplied by 3 for triple game is 1620 points as original score.

This score may be increased by the following benefits. For declaring Unique 100 points, for declaring Unique with the last tile drawn from the compartments 200 points. If suit is the player's own suit he scores an added 300 points, which added to original score makes 2220 points as the highest possible determined total score, but may further be increased by the undetermined points represented by any counters that may have been forfeited during the hand, such counters belonging to the player declaring Unique and acting as Cashier.

The highest scoring hand in mixed suits consists of 4 singles in the Pansy suit and 1 single in the Daisy suit comprising the single section, 4 doubles in Pansy suit and 1 double in the Daisy suit in the double section and the triple game in Pansy suit and no blanks in either section, the score being as follows: single section 4 tiles at 30 points each and 1 tile at 25 points is 145 points, double section 4 tiles at 60 points each and 1 tile 50 points is

290 points, plus game 90 points is a total score of 525 points.

The above hand or similar hands are not entitled to any benefits except in case of Forced Unique in which case the player having a hand of this description should become Cashier in which instance he would add 100 points for acting as Cashier and would also be entitled to the points represented by any forfeited counters that may be in the discard tray.

A player having the above or a similar hand should not declare Unique as neither section is of one suit. Should he declare Unique and all other players expose their hands, then if none of the other players has a Unique hand, so as to allow some one of the players to act as Cashier, all hands are termed "dead" and another hand must be started. Should there be any forfeited counters in the discard tray these must be left in the tray for the next Cashier.

The lowest original score in a one suit hand consists of 3 singles and 2 blanks in the single section, 3 doubles and 2 of the blanks in the double section and the single game all in the Clover suit and will score as follows: 3 tile in the single section each of 10 points is 30 points, 3 tile in the double section each of 20 points is 60 points, and single game of 10 points, making an original score of 100 points.

The lowest scoring hand in mixed suits will contain 3 singles in the Clover suit and 2 blanks of any other suit in the single section; the double section may contain a mixture of blanks, singles, or doubles, but 2 of the tile in this section are of the same number of spots or face value. The game tile is substituted for by any other tile and the score being for the 3 single tile of 10 points makes a total score of 30 points.

Blanks—Their use and value.—The "blanks" tiles having no determined scoring values within themselves, most beginners in the game of Unique are likely to discard the blanks as soon as drawn, but this is a great error as when used properly, the blanks in many instances will materially increase the player's score, will help a player to complete a Unique hand, and in certain instances will change a non-score hand to a scoring hand.

To illustrate the value of the blanks let us take the highest scoring hand in mixed suits as previously described, and suppose that the Daisy suit tile in the single section is a 3 spot and in the discard tray is a blank 3 spot in the Pansy suit. Then if the player on his turn to draw can obtain this blank and discard the Daisy suit 3 spot he will then have a Unique hand and also increase his score as follows: the single section now totals 120 points and as the game tile counts 90 points more, his total is 210 points multiplied by 3 for triple game, making 630 points, plus the 290 points in the double section, making 130

a total of 920 points, the blank in this instance really having the scoring value of 395 points as before the blank was substituted the score of the hand was only 525 points.

Should the player now declare Unique he will then add 100 points and if the single section is in the player's own suit he will add 100 points and has increased his total score with the aid of a blank, 595 points.

If the player decides not to declare Unique after his draw of the blank because he discovered another blank of the Pansy suit in the discard tray, this blank having the same number of spots on it as the Daisy suit tile in the double section and should he obtain this blank in his next draw and discard the Daisy suit tile his score would then be, single sections 120 points, double section 240 points, and game tile 90 points, totaling 450 points, multiplied by 3 for triple game, making a grand total of 1350 points, the use of the 2 blanks having increased his original hand by 825 points.

Should he now declare Unique he adds 100 points and also adds 300 points if hand is in his own suit, making a total score of 1750 points, the blanks thus having increased his original scores by 1225 points.

As the players become more proficient in the draw and discard they will find many occasions where the blanks may be used to great advantage both to increase their scores and to complete a Unique hand and also to protect themselves from a non-score hand in case of being declared Cashier should Forced Unique be declared.

The termination of the game is usually set at 5 hands or a time limit may be set should the players so desire.

Scope of hands.—In the game of Original Unique for five players, described in the foregoing rules, the same contains 10,665 different combinations of Unique hands and 153,200 different combinations of scoring hands, making a total of 163,865 different combinations of straight scoring hands, straight scores being the score of the 11 tile comprising a player's hand before doubling or adding any benefits.

Many more games than this which have been stated can be played with the apparatus which I have described, but it will be noted that all of the apparatus is essential to the games. With regard to the pins 26 on the counter racks 24 attention is called to the fact that these pins are made of just sufficient height above the base member of the counter rack to accommodate eleven of the counters only.

A player accumulating more than this number of counters of one color first fills the pin at the left end of his counter rack and then places the surplus counters of this color on the corresponding pin at the right end of his rack, this procedure determining

his winnings or losing at a glance. In certain of the games, these pins are used also as an individual tally for the player. In tallying a score in these games, the counters are used at certain values and are placed on the pins at the right end of the rack to indicate a player's score held during the hand or deal.

What I claim is—

1. A game apparatus including playing pieces divided into a plurality of different sections, each section being differently indicated there being a certain number of sections composed of an equal number of playing pieces and another section having less playing pieces than any of the other sections, all sections being in turn divided into a plurality of differently indicated suits, the suits being the same for all sections, the playing pieces of each suit in each section being numbered serially from one upward, the playing pieces of the same suit in each section having the same scoring value indicated thereon, but the scoring value so indicated being different from the scoring value of the playing pieces of the same suit in other sections, scoring value indicated on the playing pieces of any one suit in any one section being different from the scoring value indicated on the playing pieces of any other suit of the same section.

2. A game apparatus including playing pieces divided into four differently indicated sections, three of the sections being composed of an equal number of playing pieces, the fourth section having less playing pieces than the first-named sections, all of the sections being divided into five differently named and differently indicated suits, the playing pieces of each suit in each section being numbered serially from one upward, the playing pieces of each suit in each section having a like scoring value indicated thereon, which value is different from the scoring value indicated on any other pieces of the same suit in other sections, the scoring value so indicated on the playing pieces of each suit in the same section being different from the scoring value indicated on the tiles of any other suit in the same section.

3. A game apparatus including playing pieces divided into four differently indicated sections, namely a "Blanks" section, a "Singles" section, a "Doubles" section, and a "Games" section, the three first named sections having an equal number of playing pieces, the "Games" section having a less number of playing pieces than the first named sections, all of said sections being divided into five differently named and differently indicated suits, the suits being the same in each section, the playing pieces of each suit in all four sections being numbered serially from one upward, each of said playing pieces

having a scoring value indicated thereon, the scoring value of the pieces of one suit in one section being different from the scoring value of a playing piece of any other suit in the same section, the scoring value of the playing pieces of the "Doubles" section being different from the scoring value of the playing pieces of the same suit in the "Singles" section, the pieces in the "Games" section 10 of the same suit having a different scoring value with relation to each other, the pieces of any one suit in the game section having a scoring value different from the pieces of any other suit in the same section, the pieces 15 for each suit in each section having serial numbers indicated thereon.

4. A game apparatus including ninety playing pieces divided into four sections, the playing pieces of each section having indicia thereon distinguishing them from the playing pieces of the other sections, three of the sections having twenty-five playing pieces each, and one section having fifteen playing pieces, all of said sections being divided into five 20 different suits, the suits being the same in all of the sections, the pieces of the same suit in each section being serially numbered, and the pieces of the same suit in each section having thereon scoring value indications, the 25 scoring value indications in any one section being different from the scoring value indications in any other section, and the scoring value of any suit in any one section being different from the scoring value of the pieces 30 of any other suit in the same section.

In testimony whereof I hereunto affix my signature.

EDWARD P. HOLMBERG.
